IRRIGATION TUBE BASKET

William D. Gilardi, Dos Palos, Calif.

Application August 19, 1955, Serial No. 37,592

Term of patent 14 years

(Cl. D58—4)

Fig. 1 is a perspective view of an irrigation tube basket showing my new design.

Fig. 2 is a side elevational view thereof; and

Fig. 3 is an end elevational view thereof.

I claim:

The ornamental design for an irrigation tube basket, as shown.
